UNITED STATES PATENT OFFICE.

JAMES WILKINSON, OF PROVIDENCE, RHODE ISLAND, ASSIGNOR TO
WILKINSON TURBINE COMPANY, A CORPORATION OF ALABAMA.

ELASTIC-FLUID-TURBINE NOZZLE.

No. 823,909.

Specification of Letters Patent.

Patented June 19, 1906.

Application filed May 22, 1905. Serial No. 261,675.

To all whom it may concern:

Be it known that I, JAMES WILKINSON, a citizen of the United States, residing at Providence, in the county of Providence and State of Rhode Island, have invented new and useful Improvements in Elastic-Fluid-Turbine Nozzles, of which the following is a specification.

My invention relates to improvements in the construction of supply-heads and diaphragm partitions for elastic-fluid turbines, having for its object to improve the manner of constructing motor-fluid passages which are subdivided by director plates or guides. More particularly, it is an object of my present invention to simplify the manner of inserting these director-plates in the passage for the motor fluid; and it consists in providing the plates with flaring sides which enter channels formed in the side of the nozzle-passage and with an enlarged head having a transverse opening therein for the reception of a pin or screw-bolt inserted radially into the element in which the nozzle-passage is formed. This element, which may be a supply-head or diaphragm, is preferably first formed with an unobstructed opening or passage for the motor fluid, after which the channels for the reception of the sides of the director-plates are cut or milled into the sides of the passage from the discharge end. The holes for the screw-bolts are then drilled radially through the head or diaphragm and provided with screw-threads at their inner ends. The periphery of the head or diaphragm is preferably countersunk to receive the heads of the screws, the openings for which are so disposed that when the director-plates have been inserted into the nozzle-passage from the under side and their flaring sides engage within the side channels in the passage the openings in the heads of the plates will be in alinement with the screw-openings. The screw-bolts can then be readily inserted and screwed home, when the director-plates will be locked in position. The advantages of this construction consist in the cheapness of manufacture and the ease with which the parts may be assembled and replaced, for it is only necessary to remove the screw-bolts and tap the upper end of the plates to detach them.

My invention further consists in the details of construction and arrangement of parts

hereinafter more particularly described and claimed, reference being had to the accompanying drawings, which form a part of this application, and in which—

Figure 1 is a top plan view broken away of a turbine-diaphragm provided with my invention. Fig. 2 is a view along the line *xx*, Fig. 1, showing a section through a nozzle-passage. Fig. 3 is a sectional view taken along the line *yy*, Fig. 2. Fig. 4 is an end view broken away of Fig. 3. Fig. 5 is a view corresponding to Fig. 2, of a motor-fluid passage with the director-plates removed. Fig. 6 is a sectional view taken on the line *zz*, Fig. 5. Figs. 7 and 8 represent detail plan and side views of a director-plate. Fig. 9 is a modified form of a director plate or guide having a sharp admission edge disposed at an angle to its head and main body portion.

Similar reference-numerals refer to similar parts throughout the drawings.

In illustrating my invention I have shown it in connection with a diaphragm of a multi-stage axial-flow impact-turbine. It will be understood, however, that my invention is applicable to any type of turbine or other motor having a passage for the motor fluid requiring division-plates, and it will be understood that the invention is claimed without limitation to the turbine construction shown. The diaphragm 1 is provided with a central shaft-opening 2, through which the turbine-shaft 3 passes, having suitably connected thereto bucket-wheels 4, provided with peripheral rows of concavo-convex buckets 5. The diaphragm is provided with a flanged periphery 6, the flanges of the diaphragm being adapted to interlock and form the casing of the turbine. Adjacent to the periphery of the diaphragm and leading at an angle therethrough is a motor-fluid passage, which, as illustrated, is of arcuate shape and of greater length than width. This passage is formed with a flaring inlet end 7 and a discharge end 8, which latter end leads diagonally through the diaphragm and is adapted to deliver motor fluid to the buckets 5 in the succeeding stage compartment. From the discharge end inwardly I form in any suitable manner a pair of oppositely-disposed grooves or channels 9, which diminish in depth from the discharge end of the nozzle. These channels terminate flush with the side walls of the motor-fluid passage at a point near the center thereof and are

preferably arranged in relative parallelism to each other and the end walls of the passage 8.

I provide a plurality of director-plates 10, which have flaring end portions 11. As indicated in Fig. 7, the ends of the plates are sufficiently widened to engage and fit tightly within the oppositely-channeled portions of the discharge end 8 of the motor-fluid passage. These channels being disposed in the line of the fluid's flow, the lower end of the bucket will be held firmly in place, it being my purpose to force each bucket into the channels 9 until it is held firmly and rigidly therein. When this is the case, the enlarged heads 12 of the director-plates, which have transverse holes 13 therethrough, will be disposed near the center of the motor-fluid passage or substantially at the beginning of the discharge portion 8 thereof, in which position the openings 13 will be in alinement with the radial openings 14, formed in the diaphragm periphery 6. These openings 14 preferably lead from the countersunk recess 15 in the periphery of the diaphragm and are adapted to receive screw-bolts 16, which pass transversely through the diaphragm and head 12 of the director-plates and engage screw-threads at the inner end of the opening 14. These bolts serve to hold the director-plates firmly in place against longitudinal movement, while the other ends of the plates are held firmly in place against any lateral movement by the channeled portions of the passage.

35 In Fig. 9 I have illustrated a form of guide or director plate 17, having a sharp admission edge 18 disposed at an acute angle to the main body portion of the plate. This modified design of guide is more particularly adapted for use where the motor fluid is discharged with velocity from the buckets in the preceding stage compartment. The bolt-opening 13 will be formed in the head, as 12, of this plate.

45 Any desired number of director-plates may be used in the motor-fluid passages, which latter may be formed wholly or partly in the diaphragm or supply-head. Though I have throughout referred to the director-plates as having tapering sides and the grooves 9 as being of increasing depth, it will be obvious that the director-plates may be shouldered and machined, so as to fit closely within the grooves, which will then be of uniform depth, but relatively shorter. The tapering construction is, however, preferable, since the plates may then be driven in to secure them rigidly in place.

Without therefore limiting myself to the details of construction as shown and de-

scribed, what I desire to claim as new, and desire to protect by Letters Patent, is—

1. In a turbine, a motor-fluid passage, oppositely-disposed tapering recesses in the side walls of said passage, and one or more 65 tapering director-plates adapted to engage in said tapering recesses of said passage, substantially as described.

2. In a turbine having a motor-fluid passage, grooves formed in the sides of said passage which increase in depth toward the discharge end thereof, a tapering director-plate adapted to enter opposite grooves, and means to engage said plate to lock it in position against longitudinal movement in said 75 grooves.

3. In an elastic-fluid turbine, a stationary element or elements provided with a nozzle-passage, oppositely-disposed grooves formed in the side walls of said nozzle and increasing 80 in depth toward the discharge end thereof, in combination with director-plates which taper in width and are adapted to be inserted from the discharge end of said nozzle into the grooves therein, said plates being provided 85 with transverse openings, and locking-pins which project through a side wall of the nozzle to engage within said opening in each director-plate.

4. In an elastic-fluid turbine, a supply-head for a wheel-compartment, a nozzle leading therethrough, one or more director-plates in said nozzle which have rounded ends disposed near the supply end of said nozzle, one or more transverse locking-pins which engage 95 said ends of the plate or plates, and grooves in the side walls of said nozzle to receive and hold said plate or plates, substantially as described.

5. In an elastic-fluid turbine, a supply-head for a wheel-compartment having a nozzle-passage, a recess in the periphery of said head opposite said nozzle-passage, director-plates disposed in said nozzle-passage and having their lower ends in engagement with 105 the side walls thereof, transverse openings in the upper ends of said plates, and screw-bolts adapted to be inserted radially into the head and to pass through the openings in said plates to lock them in position, said bolts 110 having their heads disposed in the peripheral recess of the supply-head.

In testimony whereof I have hereunto set my hand in presence of two subscribing witnesses.

JAMES WILKINSON.
